(57) CLAIM

The ornamental design for a portable bag hanger, as shown and described.

DESCRIPTION

FIG. 1 is a top perspective view of a portable bag hanger showing the design.

FIG. 2 is a front elevational view of the portable bag hanger of FIG. 1.

FIG. 3 is a back elevational view of the portable bag hanger of FIG. 1.

FIG. 4 is a top plan view of the portable bag hanger of FIG. 1.

FIG. 5 is a bottom plan view of the portable bag hanger of FIG. 1.

FIG. 6 is a right elevational view of the portable bag hanger of FIG. 1; and,

FIG. 7 is a left elevational view of the portable bag hanger of FIG. 1.

The dash-dash broken lines in the drawings depict portions of the bag hanger that form no part of the claimed design. The dash-dot-dash lines in the drawings define the boundaries of the claim and form no part thereof.

1 Claim, 5 Drawing Sheets
